Charles Seymour

United States Patent Office.

CHARLES SEYMOUR, OF LAPORTE, INDIANA.

Letters Patent No. 64,153, dated April 23, 1867.

IMPROVED GATE-FASTENING.

The Schedule referred to in these Letters Patent and making part of the same.

TO ALL WHOM IT MAY CONCERN:

Be it known that I, CHARLES SEYMOUR, of the city of Laporte, in Laporte county, and State of Indiana, have invented a new and improved mode of Gate-Fastening; and I do hereby declare that the following is a full and exact description thereof, reference being had to the accompanying drawings, and to the letters of reference marked thereon.

The nature of my invention consists in fastening and locking the gate.

To enable others skilled in the art to make and use my invention, I will proceed to describe its construction and operation.

A represents cap, which is fastened to bed-plate C. B, sliding bar, which works between cap A and bed-plate C, with a T-head on the lower end, with two inclined planes, and notch in the centre, for the purpose of dropping on to a pin in the gate, for the purpose of fastening it. C, bed-plate, which is fastened to the post or frame. D D, thumb-levers, for the purpose of raising sliding bar B, by means of a notch in back side of sliding bar B, which thumb-levers are inserted between cap A and bed-plate C, and sliding bar B falls of its own weight. E, circular lock, which is made fast to the post at the top of bed-plate C, having a flange or foot, for the purpose of fastening sliding bar B on the pin in gate and preventing the working of thumb-levers D D, all combined as set forth.

What I claim, and desire to secure by Letters Patent, is—

The bed-plate C, cap A, sliding bar B, thumb-levers D D, and circular lock E, constructed, arranged, and operating substantially as herein set forth.

CHARLES SEYMOUR.
